UNITED STATES PATENT OFFICE.

PHILIP SCHRAG, OF NEW YORK, ASSIGNOR TO EBERHARD FABER, OF PORT RICHMOND, N. Y.

DESIGN FOR A PEN OR PENCIL HOLDER.

SPECIFICATION forming part of Design No. 13,618, dated February 13, 1883.

Application filed December 13, 1882. Term of patent 14 years.

To all whom it may concern:

Be it known that I, PHILIP SCHRAG, a citizen of the United States, residing at New York, in the county and State of New York, have invented and produced a new and original Design for Pen or Pencil Holders, of which the following is a specification, the accompanying drawings forming part thereof.

This design relates to an ornamental ferrule intended to apply to handles of pen or pencil holders; and my design consists of five members, as pointed out in the following specification and illustrated in the accompanying drawings, in which—

Figure 1 represents a side elevation. Fig. 2 is a partial horizontal section in the plane x x , Fig. 1, on a larger scale than the previous figure.

Similar letters indicate corresponding parts. In the drawings, the letter A designates the ferrule, on which is formed an ornament composed of the following five members: first, a bead, a ; second, the flat obliquely-milled member b ; third, the flat ornamented member c ;

fourth, the flat obliquely-milled member d ; fifth, the bead e .

The distinguishing features of my design are the two flat obliquely-milled members b and d , the oblique lines shown thereon in Fig. 1 indicating in reality rounded ridges f , as shown in Fig. 2. The beads a and e are plain, and of the same size. The flat member c is ornamented by rows of pearls g h .

What I claim as new, and desire to secure by Letters Patent, is—

The design for a pen or pencil holder, consisting of the bead a , the flat obliquely-milled member b , the flat ornamented member c , the flat obliquely-milled member d , and the bead e , as shown and described.

In testimony whereof I have hereunto set my hand and seal in the presence of two subscribing witnesses.

PHILIP SCHRAG. [L. S.]
